UNITED STATES PATENT OFFICE

MORRIS KORNBLUM, OF BROOKLYN, NEW YORK, ASSIGNOR TO METAL LAMP CORPORATION, OF BROOKLYN, NEW YORK, A CORPORATION OF NEW YORK

DESIGN FOR A FLOOR LAMP

Application filed April 2, 1930. Serial No. 35,120. Term of patent 3½ years.

To all whom it may concern:

Be it known that I, MORRIS KORNBLUM, a citizen of the United States, residing at Brooklyn, in the county of Kings and State of New York, have invented a new, original, and ornamental Design for a Floor Lamp, of which the following is a specification, reference being had to the accompanying drawing, forming part thereof, in which the figure is a view in perspective showing my new design.

I claim:

The ornamental design for a floor lamp, as shown.

MORRIS KORNBLUM.
